UNITED STATES PATENT OFFICE.

FRANK O. KULLANDER, OF KENSINGTON, MINNESOTA.

HARVESTER BUTTING ATTACHMENT.

961,868.

Specification of Letters Patent. Patented June 21, 1910.

Application filed January 27, 1909. Serial No. 474,514.

To all whom it may concern:

Be it known that I, FRANK O. KULLANDER, citizen of the United States, residing at Kensington, in the county of Douglas and State 5 of Minnesota, have invented certain new and useful Improvements in Harvester Butting Attachments, of which the following is a specification.

This invention relates to harvesters and 10 has special reference to an improvement on the bundle tying attachment used in connection with the same.

An object of this invention is to provide 15 means in conjunction with the bundle tying attachment of a harvester to hold the bundles firmly during the operation and to prevent the scattering of the grain comprising the same.

Another purpose of this invention is to 20 construct an attachment of this nature by the employment of which the bundles will be delivered in a compact form and be prevented from being broken as the same is delivered from the tying mechanism.

25 Heretofore it has been common for the bundles to engage the ejector arms while the same is being thrown from the platform of a harvester, and this invention has for a further object the eliminating of this feature wherein the bundles are frequently broken and caught in the apparatus where they frequently stop the operation of the complete machine.

30 For a full understanding of the invention, reference is to be had to the following description and accompanying drawings, in which:—

Figure 1 is a top plan view of the improved device having a bundle disposed upon 35 the same. Fig. 2 is a transverse vertical section adjacent one end of the same. Fig. 3 is a detailed view of the spring arm connection, and Fig. 4 is a front elevation of the connection disclosing a slight modification 40 in the proportions of the same.

45 Corresponding and like parts are referred to in the following description and indicated in all the views of the drawings by the same reference characters.

50 Referring to the drawings the numeral 10 designates the platform which is employed in connection with harvesters of common formation and which is provided adjacent one edge thereof with a bar 11 longitudinally 55 disposed thereon and supported in such position by a bracket 11^a. Intermediately posi-

tioned above the platform 10 and upon a bracket 10^a is a knotter shaft 12 which is connected to the bar 11 by a rod 12^a, and which is provided upon its outer extremity with 60 ejector arms 13, the ejector arms 13 being disposed in parallel and adapted for rotation under the action of the knotter shaft 12. The platform 10 is provided with packer arms 14 and a compressor arm 14' which extend upwardly therethrough and serve the purpose of holding and bunching the grain between the same during the operation of forming the bundle.

The improvement comprises a pair of 70 spring arms 15 which are adjustably secured upon the bar 11 and which are adapted for engagement over the bundle disposed upon the platform 10. Each of the spring arms 15 comprise a metallic rod which is formed 75 of resilient material and which is provided upon the inner extremity with a helical portion 16 to further the resiliency thereof and by means of which the same is attached to the bar 11. The free extremity of the helical portion 16 is bent laterally upon itself to form a loop 21 through which is passed a clamping bolt 17 carried by the bar 11. The clamping bolt 17 carries an arcuate plate 18 which is provided upon its inner 80 concave surface with two longitudinal grooves 19 into which are adapted to be engaged the upper faces of the arms of the looped extremity 21 formed upon the helical portion 16. The clamping bolt 17 is 85 also provided with a nut 20 which is adapted for engagement against the upper face of the plate 18 to frictionally engage the plate upon the looped portion 21. The outer extremities of the spring arms 15 are 90 curved upwardly for the purpose of preventing the engagement of the bundles thereupon and for the purpose of admitting of the even displacement of the same.

95 From the curvature of the ejector arms 13 the same are prevented from catching in the bundles as the points of the same extend backwardly when moving the bundles from the platform and the lateral curving of the same presents a broadened bearing surface 100 to insure the engagement of the arms 13 against the sides of the bundles and not to bear to any great extent at any one point. The curvature of the spring arm 15 permits the outer ends thereof from working their 105 way into the bundles between stalks comprising the same, while the lateral curving

of the spring arms present a broadened surface for engagement against the bundles.

In positioning the spring arms 15 the helical portions 16 are engaged about the bar 11 and the loops 21 are secured about the clamping bolts 17. The plates 18 which are centrally apertured, are engaged over the clamping bolts 17 and rested upon the loops 21 engaging the grooves 19 upon the arms of the loops. The nuts 20 are now revolved and caused to bind the plates 18 against the loops 21 and to frictionally engage the inner faces of the loops 21 against the upper faces of the bar 11. When it is desired to adjust the tension of one of the spring arms 15 the plate 18 is disengaged from the loop 21 and the helical portion 16 is slightly revolved in order to slide the loop 21 beneath the plate 18. When the desired tension is obtained the plate 18 is again clamped in position and the arm 15 is in condition for further use.

Fig. 4 discloses a slight modification of the arm attaching means which consists only in the lengthening of the loop 21 to provide a greater contact surface for the plate 18 whereby a firmer grasp is obtained upon the bar 11.

Having thus described the invention, what is claimed as new is:—

1. A device as specified including a bar,

spring arms carried by said bar, helical portions formed on said arms and encircled about said bar, loops formed on said helical portions, clamping bolts carried by said bar 35 and engaged through said loops, arcuate plates carried by said bolts provided with inner concaved faces and longitudinal grooves for the reception of said loops and nuts positioned against the upper faces of 40 said plates for clamping said arms in position.

2. A device as specified including a platform for the reception of bundles of grain, ejector arms disposed over said platform 45 and having their outer ends curved laterally and also in a direction opposite to the direction of rotation of said ejector arms while they are ejecting the bundle, thus forming a bearing surface for the bundles, 50 and spring arms mounted above said platform and beneath said ejector arms, and having their outer ends curved upwardly and toward one another to present a sliding surface for engagement with the bundles. 55

In testimony whereof I affix my signature in presence of two witnesses.

FRANK O. KULLANDER. [L. s.]
